US0D1064078S

(12) **United States Design Patent** (10) Patent No.: **US D1,064,078 S**
(45) Date of Patent: ** Feb. 25, 2025

(54) **GAME CONTROLLER**

(71) Applicant: **Shenzhen Jiechuangsheng Electronics Co., Ltd.**, Shenzhen (CN)

(72) Inventor: **Jie Tan**, Xiantao (CN)

(**) Term: **15 Years**

(21) Appl. No.: **29/887,071**

(22) Filed: **Mar. 16, 2023**

(51) LOC (15) Cl. **21-01**

(52) U.S. Cl.

USPC **D21/333**; D14/415

(58) **Field of Classification Search**

USPC D14/218, 388, 389, 401, 414-416, 432, D14/454, 511; D21/324, 333

CPC A63F 13/20; A63F 13/92; G06F 3/03547; H01H 9/0235

CLAIM

The ornamental design for a game controller, as shown and described.

DESCRIPTION

FIG. 1 is a top, front, right side perspective view of a game controller, showing my new design;

FIG. 2 is a bottom, rear, left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings depict portions of the game controller that form no part of the claimed design.

1 Claim, 8 Drawing Sheets
